UMBRELLA TIP CUP

Uemura Takasi, Nakanoku, Tokyo, Japan, assignor to
Goro Miura, Tokyo, Japan

Application September 15, 1953, Serial No. 380,223

9 Claims. (Cl. 135—44)

My invention relates to an improved umbrella tip-cup construction.

It is an object of the invention to provide an improved construction of the character indicated.

It is another object to provide an umbrella tip cup which cannot be moved straight up or down, but which must be deliberately actuated in a manner other than purely straight up or down in order to produce up or down movement.

It is also an object to provide a movable cup for selectively retaining umbrella-rib tips and incorporating improved means for frictionally holding said cup in the raised position.

A further object is to provide an umbrella tip cup meeting the above objects and at the same time providing positive and unambiguous location of the down position of the cup.

Other objects and various further features of novelty and invention will be pointed out or will occur to those skilled in the art from a reading of the following specification, in conjunction with the accompanying drawings. In said drawings, which show, for illustrative purposes only, preferred forms of the invention:

Fig. 1 is a fragmentary view in elevation illustrating the handle end of an umbrella to which a tip cup of the invention has been applied, part of the cup being broken away and shown in section;

Figs. 2 and 3 are perspective views of the two important parts of the tip cup of Fig. 1;

Fig. 4 is an end view of the part shown in Fig. 3;

Figs. 5 and 6 are enlarged views in partial section illustrating the coaction of the parts for two relative positions thereof;

Fig. 7 is a fragmentary view in perspective illustrating a modification; and

Fig. 8 illustrates an alternative construction for the part shown in Fig. 3.

Briefly stated, my invention contemplates an umbrella tip-cup assembly comprising a fixed cup and a rotatable cup, with propulsion means coacting between the cups so as to propel the rotatable cup axially upon relative rotation of the cups. Means are provided for arresting the rotatable cup at its limits of axial travel, and for the upper limit the stop means incorporates a locking action. Various alternative forms of the invention are shown and will be described.

Referring to Figs 1 to 6 of the drawings, my invention is shown in application to an umbrella comprising a handle 10 with a reduced shank 11 and supporting at the lower extreme end (not shown) a plurality of ribs 12 in the usual manner. Tip-cup retention means 13 of the invention is employed selectively to retain or to release the ribs 12. In Figs. 1 and 5, the parts are shown in the down position for retaining the tips of the ribs 12, and in Fig. 6 the parts are shown in the up position for releasing the ribs 12.

As indicated generally above, my tip cup 13 comprises essentially two relatively rotatable parts. Of these, a

2

fixed cup 14 is essentially a sleeve which may be fitted over the base of the handle 10 proper; and, if desired, the bottom of the sleeve or fixed cup 14 may be inwardly flanged as at 15, to provide a neat appearance and to 5 provide means for securing the same, as by means of nails 16 through holes 17, to the base of the handle 10. The other tip-cup part 18 may again be essentially a sleeve preferably close fitting and sliding over the surface of the fixed cup or sleeve 14.

10 Propulsion means carried by and coacting between the two sleeves 14—18 may serve to propel the movable sleeve 18 axially upon relative rotation of the fixed and rotatable cups 14—18. In the form shown, the propulsion means includes a cam groove 19 formed on the inner surface or bore of the movable sleeve 18, and cam-follower means 20 may be carried by or formed out of the fixed cup or sleeve 14 for coaction with the groove 19. For smooth action, I prefer that the cam follower 20 shall be of elongated oblique configuration, as shown in Fig. 2, so that the thrust force may be distributed along a substantial length of the cam groove 19 and may thus make for easy propulsion action. The cam groove 19 may be formed by a rolling operation in the sleeve 18 but, in the form shown, I illustrate my preference for a machined groove 19, so that the external appearance of the sleeve 18 may be smooth and continuous.

As a feature of the invention, I provide means for limiting the relative propulsion of the sleeves 14—18 at both ends of travel depicted in Figs. 5 and 6. For the 30 down position of Figs. 1 and 5, a positive stop may suffice and, for this purpose, I merely depress a dimple 21 in the outer sleeve 18, so as to make a localized discontinuity or projection in the bottom of the groove 19 for interception of the cam follower 20, thus preventing complete unthreading disengagement of the parts. In order to retain the other, or upper, position of the sleeve 18, I prefer to employ a locking wedge or other friction-binding means so that the rotatable cup 18 cannot be dislodged from the upper position to the downward position without a deliberate release of the friction engagement or lock. Various means may be employed for promoting the desired frictional bind, and in the form shown in Figs. 1 to 6, this is achieved by reducing the radius of the bottom of the groove 19 so as to 40 radially wedge the cam follower 20 when the parts are in the upper limiting position shown in Fig. 6.

In order to provide a reduced groove-bottom radius, a wedge indentation may be struck locally on the sleeve 18 in generally the manner described for the dimple 21; 50 alternatively, the spiral groove 19 may be formed with a bottom concentric with the sleeve axis, and the sleeve may thereafter be slightly deformed to make the sleeve section and, therefore, the groove bottom slightly elliptical. However, in the form shown, I illustrate my preference for a groove 19 of varying depth in the body of the turning cup 18. This groove construction is best illustrated in Fig. 4, in which reference numeral 22 identifies the axis for the inner and outer cylindrical surfaces 23—24 of the sleeve 18, and in which the reference numeral 25 identifies the axis for the bottom of the propulsion groove 19. The groove bottom then becomes eccentric to the axis of the cup 18, and I prefer that the shallowest part of the groove 19 resulting from such an eccentric cut shall be located at or near one of the axial ends 60 (26) of the groove 19. In the form shown, the shallowest part of the groove is located at 27, just short of one end of the groove 19, and by forming the height or external projection of cam follower 20 so as to slightly exceed the depth of the groove 19 at location 27, while at the 65 same time forming the projecting extent of follower 20 substantially less than the maximum depth 28 of the groove 19, I assure that an eccentric locking action can

take place to locate and hold the upper position of the turning cup 18; this condition is illustrated in Fig. 6, in which the cam follower 20 is jammed against the groove bottom at 19', and the outer cylindrical surface of sleeve 14 is tight against the bore of cup 18 at the location diametrically opposite 19'. I prefer that, when retained in the upper position, the bottom of the turning cup 18 and the bottom of the fixed cup 14 shall be in substantially the same horizontal plane, for appearance's sake, as also shown in Fig. 6.

In Fig. 7, I show a modified tip-cup arrangement wherein in the propulsion groove 30 is formed in the fixed cup 31, while the cam follower 32 is formed on the turning cup 33. The cam follower 32 then projects radially inwardly, but may be formed out of the body of the turning cup 33 in generally the same manner as described at 20 for the fixed cup 14. Likewise, the propulsion groove 30 may be formed in a rolling operation on the sleeve 31, but I hereby indicate my preference that the groove 30 may be cut out of the body of the fixed cup 31, as in a turning operation which, again, is preferably slightly eccentric to the axis of the fixed cup 31, in order to achieve the frictional bind described in detail in connection with Figs. 4 and 6.

In Fig. 8, I illustrate a slightly modified turning cup 35, which may be generally similar to that described in Fig. 3, except that the groove 36 may be concentric with the axis of cup 35, and the frictional bind to locate the upper position of the cup 35 may be achieved by means of a local discontinuity in the progression of the propulsion helix 36. The discontinuity in the form shown occurs at 37, where a mere change in pitch or helix angle is sufficient to produce a binding action on both sides of the oblique cam follower 20, as will be understood.

It will be seen that I have described a relatively simple umbrella tip-cup construction, featuring positive location of its limits of travel and providing assurance against accidental dislodgement, by requiring a deliberate actuating movement other than a strictly up and down actuating movement.

While I have described the invention in detail for the preferred forms shown, it will be understood that modifications may be made within the scope of the invention as defined in the claims which follow.

I claim:

1. An umbrella tip cup, comprising two relatively rotatable closely fitting sleeves, means for fixing one of said sleeves to a handle, one of said sleeves having on the surface thereof exposed to the other of said sleeves a spiral propulsion groove, projecting means carried by the other of said sleeves and riding in said propulsion groove for follower action, said groove being of varying depth for various axial locations thereof, whereby an eccentric locking action may be achieved between said projecting means and said groove for one relative angular position of said sleeves.

2. An umbrella tip cup, comprising a fixed cup and a turning cup having overlapping closely fitting relatively slideable sleeve portions, said sleeve portions having interengaging means cooperating on relative rotation of said sleeve portions to axially propel said turning cup with respect to said fixed cup, the interengaging means on one of said sleeve portions being helically developed about the axis of said one sleeve portion, the effective radius of said helically developed means about said axis varying

as a function of axial position along said one sleeve portion, there being at least one relative axial position of said sleeve portions for which said varying radius determines interference between said interengaging means, whereby a locking action may be obtained for said one axial position.

3. An umbrella tip cup, comprising a fixed cup for attachment to a handle, a rotatable cup including a sleeve slideable over said fixed cup, said rotatable cup having on the inner surface thereof a spiral cam groove, the bottom of said groove being eccentric with the axis of said sleeve, and cam-follower means carried by said fixed cup and projecting into said groove and of a radius freely to ride in said groove for a plurality of relative axial positions of said cups and yet at one relative axial position to bind against the bottom of said groove.

4. An umbrella tip cup, comprising a fixed cup for attachment to a handle, said fixed cup having on the outer surface thereof a spiral cam groove, the bottom of said groove being eccentric with the axis of said fixed cup, a rotatable cup including a sleeve slideable over said fixed cup, said rotatable cup having on the inner surface thereof a cam follower projecting into said groove and of a radius to ride freely in said groove for a plurality of relative axial positions of said cups and yet at one relative axial position to bind against the bottom of said groove.

5. An umbrella tip cup, comprising two relatively rotatable sleeves, propulsion means coacting between said sleeves to propel one of said sleeves axially relatively to the other of said sleeves upon relative rotation, first stop means coacting between said sleeves in a first relative angular position of said sleeves for determining a first limiting relative angular position of said sleeves, and second stop means coacting between said sleeves in a second relative angular position of said sleeves for determining a second limiting relative axial position of said sleeves, one of said stop means comprising a wedge carried by one of said sleeves and cooperating with one of the propulsion parts of the other of said sleeves at a given relative position of said sleeves.

6. An umbrella tip cup according to claim 5, in which said wedge comprises a portion of said groove with a bottom of varying radius.

7. An umbrella tip cup according to claim 5, in which said wedge comprises a discontinuity in the axial progression of said groove.

8. In an umbrella tip cup, two relatively rotatable sleeves, one of said sleeves having a spiral propulsion cam slot formed therein, cam-follower means on the other of said sleeves and projecting into said propulsion slot, said cam-follower means comprising an oblique projection from said other sleeve toward said one sleeve, and said propulsion slot having formed therein an axial discontinuity of such extent as to bind with said oblique cam follower.

9. An umbrella tip cup according to claim 9, in which said axial discontinuity is characterized by a change in pitch of said slot.
